Fig. 4

Fig. 3

Fig. 5

To all whom it may concern:

Be it known that I, Edward V. Platt, a citizen of the United States of America, residing at Manitowoc, in the county of Manitowoc and State of Wisconsin, have invented a new, original, and ornamental Design for an Electric Skillet, of which the following is a specification, reference being had to the accompanying drawing, forming part hereof.

In the drawing:

Fig. 1 is a side elevational view of an electric skillet showing my new design;

Fig. 2 is an exploded view thereof;

Fig. 3 is a sectional view in profile taken along line 3—3 of Fig. 1;

Fig. 4 is a top plan view of that shown in Fig. 1; and, Fig. 5 is a bottom plan view thereof.

I claim:

The ornamental design for an electric skillet, as shown.
